UNITED STATES PATENT OFFICE.

JAMES C. PINKERTON, OF PHILADELPHIA, PENNSYLVANIA.

ELECTRIC SWITCH.

No. 844,045.

Specification of Letters Patent.

Patented Feb. 12, 1907.

Application filed May 9, 1906. Serial No. 315,951.

To all whom it may concern:

Be it known that I, JAMES C. PINKERTON, a citizen of the United States, residing in Philadelphia, Pennsylvania, have invented 5 certain improvements in Electric Switches, of which the following is a specification.

One object of my invention is to provide a relatively simple and self-contained pneumatic electric switch, particularly adapted 10 for use in connection with air-brake and steam-compressor plants, it being further desired that the device shall have its parts arranged in a substantial manner and so disposed as to require but little attention or 15 pairs. These objects I attain as hereinafter set forth, reference being had to the accompanying drawings, in which—

Figure 1 is a vertical section of a switch constructed according to my invention. 20 Fig. 2 is a front elevation of the piston. Fig. 3 is a vertical section of the piston, taken on the line 3 3, Fig. 2. Fig. 4 is a side elevation, partly in section, illustrating a modified form 25 of my device. Fig. 5 is a plan view of the device shown in Fig. 4, and Fig. 6 is a vertical section on the line 6 6, Fig. 4.

Referring to Figs. 1 to 3 of the above drawings, A is a cylinder having a removable head a, to which is connected a pipe a', leading 30 from the air-reservoir of the compressor system. Said cylinder is supported on feet or brackets a² and has within it a piston B, provided with a piston-rod b, which extends through and is guided by the end of the cylinder opposite that entered by the pipe a'. Said piston-rod has on its projecting end a nut b', so placed as to limit the inward movement of the piston B.

Confined between the piston and the end a³ of the cylinder is a relatively strong spring b², tending to maintain said piston adjacent to the end a of the cylinder. There is upon one face of the piston a plate D, of insulating material, fastened to it in any desired manner, in the present instance by screws, and provided with two slots d and d', in the latter of which is a metallic plate or strip d². This latter piece is held in position by means of a screw d³, extending through but insulated 45 from the body of the piston B and provided with nuts for the attachment of an electrical conductor. Moreover, said piece d² is so supported within the slot or channel d' that while its upper end is practically level with the face 50 of the insulating-plate D its lower end is some distance below said face, and similarly the in-

sulating material forming the bottom of the slot or channel d is so shaped that its lower end is substantially level with the face of the plate D, while its upper end is some distance 60 below said level. As a consequence there is at each of the points d⁴ and d⁵, where the two slots come together at top and bottom, a relatively abrupt edge or abutment, for a purpose 65 hereinafter noted.

A spring-arm E is held to the head a of the cylinder A by means of a bolt a⁴, extending through but insulated from said head, so as to form on the outside of the cylinder a terminal for the attachment of an electrical conductor, and said arm is so made that it continually tends to place itself in the position shown in dotted lines in Fig. 1. It is, moreover, so supported that its head e, which is rounded, as shown, enters the grooves or 70 channels d and d', so as so bear against the bottom portions thereof. Connected to the bolt d³ upon the piston B is a flexible conductor f, extending through the head a³ of the cylinder, from which it is electrically insulated by means of a fiber bushing f', as shown.

Under operating conditions the electric motor for operating the compressor-pump has one terminal connected to the bolt a⁴, its second terminal being connected to one of 85 the line conductors, while the second line conductor is connected to the bolt b³ through the relatively flexible wire f. If the reservoir of the compressor system be empty, the piston B will occupy the position shown in 90 Fig. 1, and as a consequence the spring-arm E will be in contact with the lower portion of the metallic piece d². The motor-circuit is therefore complete and the motor will operate so as to cause the air-pump to compress 95 air in the reservoir connected to the pipe a'. As the air-pressure rises the piston B is moved in the cylinder A toward the end a³ thereof; but the circuit of the electric motor remains complete, for the reason that the 100 spring-arm E follows the movement of the piston in such manner that its head remains in contact with the metallic strip d². When, however, said piston has been moved to such an extent as to permit the spring-arm E to 105 occupy the position indicated in dotted lines in Fig. 1, said arm will pass off of the upper end of the strip d², suddenly breaking the motor-circuit by reason of the fact that it drops from what is practically the level of 110 the front face of the insulating-piece D to the lowermost portion of the slot or channel d.

As a consequence the operation of the motor is stopped, and no further compression of air takes place in the reservoir. As the compressed air is gradually used from said reservoir and its pressure drops the spring b^2 acts to force the piston B toward the head a of the cylinder, thereby causing the end of the spring-arm E to move downwardly through the channel d , which being bounded wholly by insulating material prevents passage of current to the motor-circuit. When, however, the piston B has moved to approximately the position shown in Fig. 1, the head e of said spring-arm drops off the elevated lower end of the bottom or floor of the channel d to the lowermost portion of the metallic piece d^2 , thereby again completing the pump-motor circuit. Said motor then starts and compresses air, so as to repeat the above cycle of operations.

If desired, I may attain the same end as that above noted by means of the combination shown in Figs. 4, 5, and 6, in which the rod attached to the piston has a portion b^6 , which at all times extends outside of the cylinder for a considerable distance. This rod is provided with a transverse slot having an insulated bushing, through which extends a longitudinally-movable bar b^7 , having brushes or contacts b^8 at its respective ends. In this form of my invention the cylinder A is provided with a supporting-base A', extended at one end and having a standard a^7 , in which the rod b^6 is guided, there being held between said standard and the rear end of the cylinder a block G, of insulating material. This block has extending along each side of its upper surface metallic strips g and g' , each provided with a terminal g^2 and so placed as to be respectively engaged by the contacts b^8 , carried by the arm b^7 . Said arm in addition to said contacts is provided with a pin b^9 , designed to operate in a groove or channel d^7 , formed in the upper surface of the block G for the reception of its lower end. The bar b^7 is longitudinally movable through the piston-rod b^6 , so as to permit of its brushes or contacts b^7 being moved into or out of engagement with the two contact-strips g and g' , which under operating conditions are respectively connected to one terminal of the pump-motor and to the line. With such an arrangement of apparatus and connections the channel d^7 is designed to maintain the contacts b^8 of the bar b^7 in engagement with the two strips g and g' as the piston-rod b^6 moves out of the cylinder—that is, when the pump-motor is operating to compress air in the reservoir. As soon as the air reaches such a pressure that the piston approaches a predetermined point in the cylinder A it will be seen from Fig. 5 that the pin b^9 will be guided by the channel d^7 toward the piston-rod b^6 , and as a consequence the bar b^7 is moved longitudinally

through said rod. The contacts of said bar are consequently moved out of engagement with the two strips g and g' , thus breaking the pump-motor circuit. Under the action of the spring b^2 the piston B is, as before, forced toward the forward end of the cylinder as the air is used, and the pin b^9 now travels in the part d^8 of the slot d^7 , thus maintaining the contacts b^8 out of engagement with the strips g and g' until the piston approaches quite near the end of its stroke. Said channel is then curved so as to slide the bar b^7 through the rod b^6 and bring the contacts b^8 into engagement with the strips g and g' , thereby again starting the pump-motor by reason of the fact that the electric circuit between the two terminals g^2 is completed through said contacts and the bar b^7 .

I claim—

1. The combination of a cylinder, a piston movable therein, a pair of switch-contacts having terminals, means for moving the piston in the cylinder, one of said contacts being movable relatively to the other and being provided with means including a channel and a piece fitting therein whereby said contact is moved into or out of engagement with the other contact as the piston is moved in the cylinder, substantially as described.

2. The combination of a cylinder, a piston therein, a spring acting between one face of the piston and one end of the cylinder, said cylinder being connected to a source of fluid under pressure, and there being a groove in the face of the piston provided with a metallic contact-piece, a spring-actuated piece, terminals for said piece and for the contact carried by the piston, said grooves being formed to permit the spring-actuated piece to engage the metallic piece carried on the piston only when said piston is moving in one direction, substantially as described.

3. The combination of a cylinder, a piston movable therein and provided with a plate of insulating material held to one face, a spring acting between one head of the cylinder and the piston, a connection between the cylinder and a source of fluid under pressure, insulating material carried by the piston and having a groove formed in it, a metallic strip placed in a portion of said groove, a terminal for the attachment of an electric conductor connected to said strip, a spring-pressed arm having a second terminal and provided with a portion operative in the groove, said groove being formed to guide said spring-pressed arm into engagement with the metallic strip only when the piston is moved in one direction, substantially as described.

4. The combination of a cylinder, a piston movable therein, there being a plate of insulating material carried by the piston and having a groove made in two parts joined to each other, a metallic strip in one of said parts of the groove having a terminal for the attach-

ment of an electric conductor, a spring-actuated contact-piece supported by the cylinder so as to be capable of moving in one part of the groove as the piston moves in one direction and in the other part thereof, as the piston moves in the opposite direction, and a terminal for said contact-piece, substantially as described.

In testimony whereof I have signed my name to this specification in the presence of two subscribing witnesses.
